171,071

ASPHALT PATCHING PLANT

Joseph S. Wylie, Oklahoma City, Okla.

Application November 17, 1951, Serial No. 17,455

Term of patent 14 years

(Cl. D14—4)

To all whom it may concern:

Be it known that I, Joseph S. Wylie, a citizen of the United States, residing in Oklahoma City, in the county of Oklahoma and State of Oklahoma, have invented a new, original, and ornamental Design for an Asphalt Patching Plant, of which the following is a specification, reference being had to the accompanying drawings, forming part thereof.

Figure 1 is a perspective view of the right hand side of an asphalt patching plant, showing my new design;

Figure 2 is a similar view of the left hand side;

Figure 3 is a perspective view showing the left hand side, the rear end, and a portion of the top; and

Fig. 4 is a plan view.

I claim:

The ornamental design for an asphalt patching plant, as shown.

JOSEPH S. WYLIE.
